US00D734154S

(12) **United States Design Patent**
Johnson et al.(10) **Patent No.:** US D734,154 S
(45) **Date of Patent:** ** *Jul. 14, 2015(54) **BEVERAGE CONTAINER**(71) Applicant: **Ball Corporation**, Broomfield, CO (US)(72) Inventors: **Dean L. Johnson**, Littleton, CO (US);
David J. Bonfoey, Thornton, CO (US)(73) Assignee: **Ball Corporation**, Broomfield, CO (US)

(*) Notice: This patent is subject to a terminal disclaimer.

(**) Term: **14 Years**(21) Appl. No.: **29/454,059**(22) Filed: **May 6, 2013****Related U.S. Application Data**

(63) Continuation of application No. 29/386,520, filed on Mar. 2, 2011, now Pat. No. Des. 684,059.

(51) **LOC (10) Cl.** ..... **09-01**(52) **U.S. Cl.**USPC ..... **D9/500**(58) **Field of Classification Search**USPC D9/500, 502-505, 516, 549, 557-558,
